UNITED STATES PATENT OFFICE.

JOHN P. HOKANS, OF WASHINGTON, DISTRICT OF COLUMBIA.

CHAIR.

No. 800,373.

Specification of Letters Patent.

Patented Sept. 26, 1905.

Application filed May 26, 1904. Serial No. 209,913.

To all whom it may concern:

Be it known that I, JOHN P. HOKANS, of Washington, in the District of Columbia, have invented certain new and useful Improvements in Chairs; and I hereby declare that the following is a full, clear, and exact description thereof, reference being had to the accompanying drawings, which form part of this specification.

10 This invention is an improvement in chairs; and its objects are to provide an easy comfortable chair having an adjustable seat which can be shifted forward or back to suit the occupant.

15 The chair embodies various novel features of construction of the back, the seat, the seat-adjusting devices, the arm and arm-supports, the seat-supports, and other features and details of construction which will be herein-
20 after explained, and the particular parts and features for which protection is desired are summarized in the claims.

In the drawings, Figure 1 is a perspective view of the chair. Fig. 2 is a longitudinal vertical section thereof. Fig. 3 is an enlarged detail-transverse section through the seat and frame, showing the seat-adjusting devices. Fig. 4 is a detail view of the seat-adjusting shaft. Fig. 5 is a view of the connections between arm and standard detached. Figs. 6 and 7 are enlarged detail views of the back-attaching devices. Fig. 8 is a view of the arm parts detached. Fig. 9 is a detail view of one of the rear seat-supports and rear leg detached. Fig. 10 is an enlarged detail sectional view through one of the support-slides. Fig. 11 is a detail view of one of the side bars. Fig. 12 is a detail view of one of the front legs. Fig. 13 is a detail sectional view showing the connections between the bar, front leg, and front support.

The chair is shown as a rocking-chair; but I do not restrict myself to rockers.

45 The front and rear legs A B at each side of the chair are connected to and by an arched metal bar C, which, as shown, has its ends fitted in slots a b in the upper ends of legs A B and firmly united thereto by bolts or screws a' b' , as shown. Thus the legs and bar practically constitute a solid side frame. The lower ends of the legs A B may be fastened to rockers D in any suitable manner, said rockers being preferably constructed like

those shown in my application for patent, Serial No. 171,131, filed August 28, 1903.

55

The seat E is curved upwardly at rear and downwardly at front, having the curvature indicated in the drawings to make it most comfortable. It is supported upon and connected to the side frames by means of front supports F and rear supports G. These supports are preferably arched, so that each has two bearing-points upon the side frame. As shown, supports F have their inner ends slotted, as at f , to receive and fit the bar C, 65 which is slidably confined in such slot by a keeper f' , and to the front end of the supports F are attached metal loops f'' , which depend into slots a^2 in legs A and encircle the bar C, slots a^2 being sufficiently long to permit sliding movement of the loops (and supports F) on the side frames. Set-screws f^3 are tapped through the lower ends of the loops and are loosened when the seat is to be adjusted and tightened after the seat has 75 been adjusted to the desired position. Follower-plates f^4 may be placed between the screws and bars to give a greater clamping effect to the screws. The supports G are similarly provided with slots g on their inner ends to receive the bar C, which is retained therein by a keeper g' , and the outer ends of supports G are provided with metal loops g'' , fitted to the bars C within slots b^2 in legs B, having set-screws g^3 in their lower 85 ends.

Attached to and depending from the seat intermediate the supports F G are hangers H H, in which is journaled a transverse shaft I, which is surrounded between hangers H by a 90 sleeve H'. Said shaft projects slightly beyond the bars C and lies close to the lower edges thereof. On the ends of the shaft just outside the hangers are placed cones i , which may be formed integral with small pinions i' 95 exterior to the cones and with washers i^2 exterior to the pinions. One or both sets of cones, pinions, and washers may be slidably but not rotatably splined on the shaft I, and they are confined thereon between hand-wheels I', one or both of which may be screwed onto the shaft, so as to be adjustable to force the cones and pinions inward or, if loosened, will let them separate slightly.

It will be observed by reference to Fig. 3 105 that when the hand-nuts I' are tightened the

cones *i* are forced in under the bars *C*, which may have their edges beveled, and the cones serve as wedges to draw the seat down hard upon the side frames, which will give the seat 5 additional bearing on the side frames and prevent the seat casually sliding or shifting thereon. The sleeve *H'* prevents the cones moving too far inward and also prevents the tightening of the nuts straining the side frames laterally. When the nuts *I'* are loosened, the cones ease away from the bars *C* and pinions *i'* mesh with short segmental racks *c'*, attached to the side frames, and by then rotating shaft *I* the seat can be slid backward or forward on the 15 side frames to the desired position and secured when adjusted by tightening up the nuts *I'*. It will be observed that the seat when fast virtually has five points of bearing on each side frame—two through each support 20 *F* and *G* and one just above the shaft *I*. Owing to the peculiar curved shape of the frame and the manner of slidably supporting the seat thereon, it will be observed that as the seat is moved backward its rear end will be 25 depressed and its front end elevated. In other words, the seat is measurably oscillated upon the shaft *I*, and this peculiar nature of its adjustment is desirable in order to obtain a more perfect balance of the chair, so as to suit its 30 occupant.

Owing to the peculiar curvature of the seat, it is difficult or rather impractical to bend it or to cut it out of one piece, so that it will be strong enough. I therefore prefer to build 35 it up out of a number of transverse sections or strips *e*, which are roughly diamond-shaped in cross-section, so that the joints between the strips are not vertical, but inclined to the perpendicular almost at angles of forty-five degrees. This causes the upper edge of one 40 joint to extend beyond the lower edge of the next rearmost joint. In other words, the joints overlap. Longitudinal binding-strips *e'* may be seated in recesses along the side edges of 45 the seat, as indicated in the drawings, to assist in bonding the sections together and preventing their starting apart at the ends of the joints. A seat so constructed can be given any desired contour, and I have found by actual practice that the sections will split before 50 the joints will loosen.

The back of the chair is preferably formed of a series of bent-wood strips *J*, which may be arranged in loop form. The lower ends of 55 every loop or pair of strips *J* are preferably recessed, as at *j*, to engage the head ends of screws *K*, that are screwed into the back edge of the seat before the loops are attached. The recesses *j* in the meeting ends of the strips 60 close the projecting heads of the screws, and when the strip ends are fastened together, as by screws or bolts *L*, the strips will be firmly

secured in place. Bent wood or metal braces *L'* may be interposed between adjacent pairs of strips *J* at the lower ends thereof and fastened to the braces by the screws or bolts *L* and may also be fastened to the seat by screws *L''*. The upper parts of the loops can be connected in any suitable manner and may be stiffened by braces or stays *M*, as indicated in 70 the drawings.

The arms *N* of the chair are fastened to the back and to standards *O*, rising from the seat and suitably fastened thereto by the screws *o'o'*. These standards *O* are preferably shaped 75 as shown, and in order to insure their strength and a firm connection between them and arms *N*, I preferably employ fastening-plates *P*, which are attached to the upper ends of the standards by a long screw *p'* and are secured 80 in recesses *n* in the under side of the arm by screws *c*, as shown. The arms *N* are curved at rear, and in order to strengthen them they may be slotted, as at *N'*, and this slot filled with a stiffener *N''*, formed by cementing together a number of diamond-shaped sections 85 with inclined overlapping joints, substantially after the manner in which the seat is made.

The rear ends of legs *G* may be stiffened by a transverse brace *G'*, attached to the legs and 90 seat, as indicated in the drawings, and the front supports may be braced by the screws *F'*, attached thereto and to the seat, as indicated in the drawings.

The manner of using the several parts and 95 their utility has been set forth above, and further explanation thereof appears unnecessary.

Having thus described my invention, what I therefore claim as new, and desire to secure by Letters Patent thereon, is—

1. A chair-arm, composed of a slotted piece 100 of wood, and a strengthening-filling in said slot, composed of a series of segmented sections having overlapping joints, substantially as and for the purpose described.

2. A chair-arm, composed of a piece of bent wood, having a slot or recess in its bend, and a strengthening-filling for said slot, composed of a series of segmental sections having overlapping joints, substantially as and for the purpose described.

3. The combination in a chair of the seat, the back, the standards attached to the seat, the arms attached to the back and projecting over the standards, and the fastening-plates 115 attached to the tops of the standards by long screws, and secured to the under side and forward end of the arm, substantially as described.

4. In a chair, the combination of the seat and the projecting fasteners attached thereto; 120 with a back composed of pairs of members having their lower ends recessed to embrace the projecting fastenings, and means for uniting said members.

5. In a chair, the combination with the seat and projecting headed screws attached thereto; with a back composed of bent-wood strips having their lower ends recessed to embrace the projecting screws, and means for bracing the strips and clamping their lower ends around the screws, substantially as described.

In testimony that I claim the foregoing as my own I affix my signature in presence of two witnesses.

JOHN P. HOKANS.

In presence of—

L. E. WITHAM,
JAMES R. MANSFIELD.
